BEATER

Annette Anderson, Minneapolis, Minn.

Application May 14, 1954, Serial No. 30,489

Term of patent 14 years

(Cl. D44—1)

To all whom it may concern:

Be it known that I, Annette Anderson, a citizen of the United States, residing in Minneapolis, county of Hennepin, State of Minnesota, have invented a new, original, and ornamental Design for a Beater, of which the following is a specification, reference being had to the accompanying drawing, forming a part hereof.

I claim:

The ornamental design for a beater, as shown.
